San Francisco, Calif., a corporation of Nevada

Application July 7, 1941, Serial No. 401,320

11 Claims. (Cl. 146—76)

This invention relates to extractors of the type in which juice bearing materials such as fruits and vegetables are subjected to comminuting and centrifugal screening operations while under pressure to extract the juice and a desired proportion of certain solid constituents of the material.

It is an object of the invention to provide an extractor of the character referred to which is constructed to provide a definite control of the type of extracting operation to be performed.

Another object of the invention is to provide an extractor of the character referred to in which the various stages of comminution can be adjusted separately in accordance with the character of material being processed.

Another object of the invention is to provide an extractor of the character referred to which is constructed to simplify assembly and servicing as well as provide for economical production.

Another object of the invention is to provide an extractor of the character referred to in which the screening means is of a special construction to reduce foaming of the extracted material and to provide a greater percentage of extraction without increasing horsepower requirements.

Another object of the invention is to provide an improved extractor of the character referred to which provides a high percentage of juice recovery with reference to the material processed with a minimum horsepower requirement.

Other objects and advantages of the invention will be apparent from the following description of a preferred embodiment thereof, as illustrated in the accompanying drawings, in which:

Figure 1 is a vertical sectional view through an extractor constructed in accordance with the instant invention;

Figure 2 is a horizontal sectional view taken in a plane indicated by the line 2—2 in Figure 1;

Figure 3 is a horizontal sectional view taken in a plane indicated by the line 3—3 in Figure 1;

Figure 4 is a horizontal sectional view with the two halves of the view taken in two planes, as indicated by the line 4—4 in Figure 1;

Figure 5 is a fragmentary sectional elevation taken in a plane indicated by the line 5—5 in Figure 4, certain parts being omitted for greater clarity.

Figure 6 is a full-size fragmentary sectional view illustrating the relation of the parts in the comminuting and extracting zones;

Figure 7 is a sectional detail view of a portion of the screen mounting means, the plane of section being indicated by the line 7—7 of Figure 5;

Figure 8 is a developed full-size elevational view of a portion of the comminuting and screening parts mounted on the stator or housing of the machine, the view being indicated by the line 8—8 of Figure 6;

5 Figure 9 is a fragmentary sectional view taken as indicated by the line 9—9 in Figure 8;

Figure 10 is an enlarged view of a portion of the screen;

10 Figure 11 is an enlarged view of a portion of a modified form of screen;

Figure 12 is a developed full size elevational view of a part of the rotor showing the relation of the breaker and comminuting means, the view being indicated by the line 12—12 of Figure 6;

15 Figure 13 is a fragmentary plan view of the upper comminuting ring and impeller and is taken in a plane indicated by the line 13—13 in Figure 12;

Figure 14 is a fragmentary plan view of a comminuting member and an impelling member taken as indicated by the line 14—14 in Figure 12;

20 Figure 15 is a fragmentary plan view of a portion of the bottom ring taken as indicated by the line 15—15 in Figure 12.

25 The extractor shown herein is of the general type disclosed in the copending application of Henry G. Schwarz, Ser. No. 54,795, filed December 17, 1935, for Centrifugal extractors and methods of extraction, which issued December

30 23, 1941, as Patent No. 2,267,048. In this type of extractor, the juice containing material is fed downwardly and outwardly through an annular radially expanding path formed between a rotor

35 and a stator or housing. Along the path are disposed successive material comminuting zones in which means comprising cooperating elements on the rotor and the housing in each case serve to break open juice cells and liberate juice as well as providing a certain proportion of finely divided constituents. After each comminuting zone a centrifugal screening zone is provided for the separation of the liberated juice and the finely divided solid constituents. The separation

40 is effected by peripheral screens past which the material is carried by impelling blades on the rotor which not only wipe the comminuted material circumferentially and downwardly past

45 the screen but also subject the material to a centrifugal force urging it through the screen. At the discharge or lower end of the annular path an adjustable restriction is provided whereby the rate of flow of material through the machine can be controlled and a pressure zone can

50 55

be established through the screening and comminuting zones.

Referring to Figure 1, the extractor is provided with a base or stand 10 upon which the lower flange 11 of a lower housing member or casing 12 is secured by means of bolts 13 (Figures 3 and 4). The upper flange 14 of the housing member 12 supports a ring 16 on which flange 17 of the upper housing member 18 rests. Bolts 19 secure the flange 14, the ring 16, and the flange 17 together (see Figure 3). Upon its top surface the upper housing member 18 is provided with upstanding pads 21 on which the electric motor 22 is secured by means of cap screws 23.

Within the housing a rotor, indicated generally at 26 (Figure 1), is mounted for rotation by the motor 22 and carries various sets of elements cooperating with parts of the housing to perform the material comminuting and separating steps as later described. The rotor 26 (Figure 1) includes a hub 27 of a generally inverted cup-shaped construction which is secured to an annular flange of the rotor shaft 28 by means of cap screws 29. The lower reduced end of the shaft 28 is slidably journaled by a suitable bushing in the recessed upper end of the lower shaft 31. Shaft 31 has a reduced lower end to which the inner race of a bearing 32 is secured by means of a sleeve 33 and an end plate 34 suitably secured to the lower end of shaft 31. The outer race of bearing 32 is mounted in upper and lower bearing retainers 36 which are secured to the hub 37 of a bottom bearing bracket 38 by bolts 39. Suitable seals are provided between the bearing retainers 36, the shaft 31, and the sleeve 33 at either side of the bearing 32. Bottom bearing bracket 38 is provided with an adjustable mounting in the housing as later described.

The rotor shaft 28 (Figure 1) is provided with a reduced upper end 41 to which the inner race of a bearing 42 is secured by means of a rotor coupling gear 43 which is secured on the shaft by a suitable end retaining plate. Rotor coupling gear 43 is also provided with a suitable keyed connection to the shaft 28. The teeth of the rotor coupling gear 43 mesh slidably with the internal teeth of a motor coupling fitting 44 having a keyed and snug fit on the lower end of motor shaft 46. The outer race of bearing 42 is secured between bearing sleeve 47 and bearing cap 48 secured thereto by suitable cap screws. A suitable seal is seated in cap 48 to engage the shaft 28. Bearing sleeve 47 has a threaded connection at 49 within a depending supporting collar 51 having a flange at its upper end secured to the top wall of the upper housing member 18 by cap screws 52 (Figure 2). The threaded connection of the bearing sleeve 47 within its supporting collar 51 provides a means of adjustment to be utilized in the machine as later described whereby the rotor can be adjusted vertically.

With the above general description of the parts in mind, a detailed description of the various operating parts will now be made in sequence as the material flows through the machine.

Material is fed to the machine through hopper 61 (Figure 1) which is suitably supported on and communicates with a feed housing 62 having a feed screw 63 suitably mounted therein. Screw 63 is preferably driven from a conventional variable speed drive mechanism (not shown). Feed housing 62 (Figures 1 and 2) communicates with the interior of the upper housing member 18 and is secured thereto by means of cap screws

64. Material fed in through the hopper 61 to the feed screw 63 is discharged into the feed chamber within the upper housing member 18 from which it falls by gravity into a breaker chamber where a preliminary coarse breaking up of the material is performed by cooperating elements carried by the rotor and on the housing.

The breaker chamber is formed within a breaker ring 66 (Figures 1, 3, 6 and 8) having a close sliding fit at 67 within an aperture in the lower wall of upper housing member 18, having a threaded connection at 68 with the ring 16 and having a close fitting connection at 69 with an aperture in the upper flange 14 of the lower housing member 12. Breaker ring 66 provides a pilot for accurate alignment of the upper and lower housing members in assembly. As seen most clearly in Figures 3 and 8, the inner face of the breaker ring 66 is provided with a series of upright teeth or ribs, each tooth having an upwardly facing frusto-conical surface 71 connected to a central downwardly facing frusto-conical section 72, a lower frusto-conical surface 73 which is joined at its lower end to a short and more deeply inclined frusto-conical surface 74. As seen most clearly in Figures 8 and 9, the various portions of the cutting edge of each of the breaker teeth, that is the edge facing the direction of circumferential flow of material, lie in a plane, while the trailing edge is provided with an inclined surface 76 which terminates short of the adjacent breaker tooth to provide a feed trough for material which leads downwardly and radially outwardly.

Cooperating with the breaker ring 66 (Figures 1 and 3) is a breaker 77 formed of a plurality of breaker blades or impellers integrally cast with a hub 78 having a snug fit on a portion of the shaft 28. The breaker blades are angled at about 30° from the vertical with their upper edges leading. At the same time each blade has a compound relation to a radial line to cause the outside edge of the upper portion of the blade to trail in the direction of rotation, while the outside edge of the lower blade is in leading position, the angle being about 10° at the lower portion. The breaker 77 is provided with a bottom wall 79 which is of an inverted cup shape to conform to the shape of the rotor hub 27. Breaker 77 is secured to the rotor by means of tapped bosses 82 formed at the trailing side of each blade and which receive suitable fastening screws. The bottom wall 79 has its lower machined edge seated flush on the machined upper surface of a T-shaped top ring 86. The flush engagement of wall 78 and ring 86 provides a seal so that the material being treated can not contact rotor hub 27. Ring 86 has one flange of its T seated in the rotor hub 27 and the base of the T seated on a center ring 87 which in turn seats on a peripheral flange 88 of the rotor hub 27. Bottom ring 89 is seated against the lower face of flange 88 and all of the rings are secured in place by cap screws or bolts 91 which extend through the bottom ring 89, the flange 88, the center ring 87, and have threaded engagement within the top ring 86. The functions of the rings 86, 87 and 89 will be referred to hereinafter.

Referring to Figure 3, it will be seen that the three breaker blades provided have their upper edges in leading position and slant rearwardly with respect to the direction of rotation to provide a radially outward and downward flow of material through the breaker chamber while wiping the material past the breaker teeth of the ring

66. This operation serves to effect a coarse breaking up of the material as it is fed into the machine as a preliminary to the first comminuting step. The construction of the breaker chamber with a lower annular portion leading radially outwardly and downwardly from the upper portion insures a full rapid flow of material from the breaker chamber to the first comminuting zone, and also facilitates the formation of a liquid seal against the entrainment of air with the material.

Vertical adjustment of the breaker ring 86 may be effected by means of the castellated construction of its upper end provided by the teeth therein. Access to the ring may be had by removing the frame cover 92 which closes an opening in the upper housing member 18. Cover 92 (Figure 1) carries a locking pin 93 so that the pin is disposed between an adjacent pair of breaker teeth when the cover 92 is in place to thereby lock the breaker ring in its selected position.

From the breaker chamber, the material is fed radially downwardly and outwardly between co-operating sets of comminuting teeth formed on the top ring 86 and the lower edge of the breaker ring 86. As seen most clearly in Figure 6, the portion of the breaker teeth formed on the lower frusto-conical surface 74 are opposed to teeth 96 formed in the upper flange of the T-shaped upper ring. As seen in Figures 12 and 13, the teeth 96 are formed by milled grooves in a frusto-conical outer face 97 of the top ring 86. Teeth 96 are cut inclined to form impellers as well as cutters and are preferably cut by a cutter located at an angle of 30° to the vertical. The teeth are cut through the lower edge of the surface 97 to insure a feed channel for material even with the gap substantially closed. In practice, for example, 24 teeth may be provided on a top ring of a diameter of about 13½ inches.

The spacing apart of these teeth and consequently the degree of comminution is controlled by vertical adjustment of the breaker ring 86 and for ordinary operations the spacing apart between the frusto-conical faces 74 and 97 will be about .090 inch. The opposed teeth of the top ring 86 and the breaker ring 86 provide a comminuting operation which crushes and breaks open a portion of the juice containing cells of the material and frees a certain proportion of this juice. At the same time the material is being comminuted, it is directed radially outwardly and downwardly by means of the inclined relation of the milled grooves forming the teeth 96.

From the first comminuting step performed as described above, the material is fed into a vertical annular juice extracting chamber formed between the rotor and an annular screening means supported in the housing. In the centrifugal screening chamber, material is carried around the screen while being progressed downwardly by means of a series of impelling blades 101 which are preferably formed integrally on a ring 102 held between the top ring 86 and the center ring 87. As seen most clearly in Figure 12, the forward faces of the impelling blades 101 are inclined with respect to the vertical and have their lower edges trailing. The angle of inclination is generally from 5 to 10°. The forward faces of the impelling blades are also angled at about 10° to a radius line with the outer portion in leading position.

The outer face of the impelling ring 102 substantially continues the outer surface of the top ring 86 and the center ring 87 with only a slight

undercut below the upper flange of the ring 86 to facilitate the impelling action of the blades.

The screening means is preferably in the form of a perforated strip or screen 103 which is disposed in opposite grooves milled in the upper and center flanges 104 and 106 of a screen frame section 107. The screen 103 shown in detail in Figure 10 may be formed of rubber or metal and may be provided with holes ranging in diameter from about .004 of an inch upwardly. The holes are preferably funnel-shaped with the small end facing the rotor. This construction is in effect self-cleaning and avoids plugging of the holes. The screen 103 is provided with a perforated backing strip 108 which is also received in milled grooves in the respective flanges 104 and 106. The perforations in the backing strip are elongated in a circumferential direction.

The preferred form of screen is shown in Figure 11 at 103a where the holes are elongated in a direction to extend circumferentially of the machine. In this type of screen the width of the hole is controlling as to the particle size which can be passed through the screen. In a typical installation the hole dimensions would be .004" wide by .010" long. With this screen construction the percentage of extraction is increased and foaming of the material is minimized.

The screen frame 107 is made in two similar semi-circular halves or sections (Figures 4, 5, and 7) having end flanges 109 secured together by bolts 111. The backing strip 108 is supported at spaced intervals by vertical ribs 112 extending between the flanges 104 and 106 of the screen frame. As seen most clearly in Figure 7, the end flanges 109 have their adjacent faces recessed along their inner portions to receive a vertically disposed key 116 which is secured to one of the end flanges by a plurality of screws 118. Key 116 is provided with an angled slot 117 which receives the end of the screen section which faces into the direction of travel of the material and which is mounted in the frame section before assembly into the machine. After the assembly the key provides an abutment for the adjacent or trailing end of the other semi-circular section of screen 103 mounted in the other screen frame sections in a similar manner. In this way, the leading ends of the screen sections are not exposed directly to the flow of material circumferentially about the extracting chamber. At the same time an extra length is provided in each screen section to insure a full screen surface throughout the periphery of the chamber.

From the above description, it will be obvious that each screen section can be slid endwise into the associated screen frame section during assembly with one end seated in the milled slot 117 in the associated key. The backing strip 108 also is slid endwise into the frame section to abut the key 116 at one end and terminates at the other end of the frame section so as to provide full support for the screen. After assembly the backing strip in effect becomes a part of the screen frame section itself. When assembled as separate units the screen frame sections are identical and may be assembled in the machine at any convenient circumferential position for easy access to the clamping bolts.

From the extracting chamber formed between the screen 103 (Figure 6) and the impelling ring 102, the material is fed downwardly and radially outwardly between a second set of comminuting teeth. One set of these teeth is indicated at 121 on the central flange 106 of the screen frame

where they are formed by milled vertical slots in a frusto-conical surface 122. The opposite teeth 123 (Figures 6, 12 and 14) are formed by milled inclined slots in a frusto-conical surface 124 on the center ring 87 in the same manner as described in connection with teeth 96. There are 24 teeth 121 and 123.

From the comminuting teeth 121 and 123, the material is fed radially downwardly and outwardly to a screening or juice extracting chamber of greater diameter than the first extracting chamber. The second chamber is formed between an impelling ring 126 (Figures 1, 6 and 12) secured between the center ring 87 and the bottom ring 89 and having impelling teeth 127. Ring 126 is formed and mounted similar to the ring 102, except that the upper edges of teeth 127 are bevelled for greater clearance. The screening means for the lower screening chamber is formed of a screen element 128 (Figures 1, 6 and 8) and supporting strips 129 mounted in the center flange 106 and the lower flange 131 of the screen frame sections as described in connection with the screen 103 and the strip 108.

The lower flanges 131 (Figures 1 and 6) of the screen frame sections seat in an upper flange 133 of a bottom support ring 132 which is suitably bolted to the lower housing member 12. The upper faces of the screen frame flanges 104 seat against a machined surface of the upper flange 14 of the lower housing member 12 and overlap the breaker ring 66. The screen frame sections are removably seated with respect to the above described elements and are held in place when bolted together. Access to the screening means can be had by means of removable covers 134 (Figures 4 and 5) which are secured by cap screws to the lower housing member 12. Covers 134 have semi-circular walls extending adjacent the screen frame to provide a reduced volume in the juice chamber. By removing the covers 134, the screen frame sections can be unbolted and removed endwise from the machine for repair or replacement of the screen.

The juice and solid materials which pass through the respective screens 102 and 128 are received in a juice removal chamber formed within the lower housing member 12 which is provided with four outlet conduits 136 for receiving respective pipes.

The solid material which is progressed downwardly through the lower extracting chamber by the impelling blades 127 is discharged through a restricted outlet which may also be provided with comminuting means. This bottom outlet is formed by a frusto-conical face 137 (Figure 6) formed at the inner face of flange 131 of the screen frame and having upright teeth 138 (Figures 6 and 8) and an opposed frusto-conical face 139 provided with teeth 141. These teeth always serve as impelling teeth and may be used for comminution if desired. Face 139 is provided on an upper flange 142 of a bottom plate 143 which is secured at its inner end by screws 144 (Figure 1) to a flange 145 of the lower shaft 31. The plate 143 is apertured to receive the heads of cap screws 91 to provide a driving relation from the rotor hub 27 to the lower shaft 31 while providing for relative axial movement therebetween.

Lower shaft 31 and bottom plate 143 are mounted for vertical adjustment to provide an adjustable restriction at the bottom outlet for the residual solid materials whereby the desired amount of back pressure can be created throughout the screening and comminuting zones. The

bottom support ring 132 has a threaded connection at 146 with the bottom bearing bracket 38 in which lower shaft 31 is journaled. Thus, by vertical positioning of the bottom bearing bracket 38, the lower shaft 31, and the bottom plate 143, the spacing between the frusto-conical faces 139 and 137 can be controlled. This spacing is usually at about .020 of an inch or less. To enable adjustment thereof, bearing bracket 38 is provided with a gear flange 147 meshing with a pinion 148 journaled about a pin 150 supported in the lower housing member 12. The pinion 148 is perforated to register with a locking recess 149 in the lower housing member 12 with a locking pin in place the selected amount of restriction provided by the bottom outlet is held constant during operation.

In order to adjust the spacing between the teeth 121 and 123 of the second comminuting zone, the upper portion of bearing sleeve 47 is provided with a gear portion 151 which meshes with an idler pinion 152 suitably journaled on the upper housing member 18 and meshing with an adjusting pinion 153. As seen most clearly in Figure 2, pinion 153 has upstanding locking teeth 154 for engagement by a locking member 156 pivoted at 157 on an L-bracket 158. By rotating pinion 153 and bearing sleeve 47, rotor 26 can be raised or lowered in accordance with the desired spacing of the teeth 121 and 123.

Operation

The operation of the machine will be summarized briefly with reference to the extraction of a solids-bearing juice from material such as carrots, celery, beets or apples. With the motor in operation, the material is introduced through the hopper 61 (Figure 1) and the feed housing 62 into the feed chamber within the upper portion of the housing 18 above the breaker chamber. The rate of feed by screw 63 is preferably adjusted to keep the top chamber substantially full so that a constant and full flow of material will be had at all times to the breaker chamber and the various comminuting and extracting zones.

The material drops from the feed chamber into the breaker chamber and is carried about and forced outwardly and downwardly by the breaker blades 77 (Figures 1 and 6) which sweep the material about the chamber and against the series of breaker teeth carried by the breaker ring 66. This results in a preliminary breaking up of the material, the liberation of some juice and the separation of some fine solids. The trailing relation of the outer edges of blades 77 at their upper portion provides for quick initial outward movement of the material and a quick break-up. The broken up material flows radially outwardly and downwardly without interruption into the first comminuting zone provided by the teeth 96 and 97 (Figure 6). The trailing relation of the lower ends of blades 77 promotes this even flow and provides a self-cleaning action in the breaker chamber. At the same time as the material progresses downwardly, its centrifugal action is coordinated with its downward flow by the leading relation of the outer edge of the blade 77 at its lower portion. This action occurs principally at a location opposite to the converging portion of the passageways provided between breaker teeth 66, and is believed to insure a substantially even distribution of the material for action by the breaker teeth. At this place the first comminution occurs which results in the liberation of a substantial amount of juice and

further fine solids. The comminuted material is directed radially outwardly and downwardly to impinge directly against the upper portion of the screen 103. Again, a coordinated and delayed passage of the material across the impelling blades is provided by making the upper edge of the blade leading vertically and the outer edge leading in the direction of rotation. In the first extracting chamber between the screen 103 and the impelling ring 102, the material is carried about the chamber, at an angular velocity dependent upon the speed of the rotor and the radius of the blades 101, by the impeller blades 101. For a blade radius of about 13 $\frac{3}{4}$ " and an inner screen diameter of 14", a motor speed of 1800 R. P. M. is satisfactory. The material is swept obliquely toward the screen so that the solids tend to, and actually do, form a filter bed against the lower portion of the screen. The upper portion of the screen remains substantially clear of solids because of the direct impingement and washing action of the material discharged directly against the screen from the teeth 96 and 97.

As the material is progressed downwardly over the screen by the action of the impeller blades and the oncoming material, the free juice and fine solids are carried outwardly by centrifugal force through the screen, the size of opening in the screen being determinative of the size of particle which can pass therethrough. The remaining solids material from which a portion of the juice and certain of the fine solid constituents have been removed then passes downwardly and radially outwardly between the second set of comminuting teeth 121 and 123 whose spacing is generally adjusted to provide a finer comminution than the teeth 96 and 97.

The final grind at the teeth 121 and 123 is adjusted in its relation to the material being processed to obtain the desired liquid and solid constituents which are to form the juice received from the discharge, and this material is progressed peripherally about the second extracting chamber between the screen 128 and the impelling ring 126, being also progressed circumferentially and downwardly by the impelling teeth 127. This results in a further centrifugal extraction of liberated juice and finely divided solid constituents. A filter bed of the comminuted material also forms on the screen 128 and is progressed downwardly across the screen toward the restricted discharge between the surfaces 137 and 139.

The adjustment of the restriction formed between the surfaces 137 and 139 by vertical movement of the bottom ring 143 provides a back pressure which extends at least through the second extracting and the second comminuting zones and may extend up to the first extracting and the first comminuting zone.

The retardation of the flow of material downwardly subjects the material for a longer time to the sweeping action of the impelling blades 127 and retards its passage through the comminuting teeth 121 and 123 so as to obtain the desired extraction in accordance with the particular material being processed. As a result, a substantially juice-free solids cake is extruded at the bottom outlet of the machine, while the juice material is passed into the juice chamber of the housing 12 through the screens 103 and 128. The teeth 138 and 141 act principally as impelling means to aid in progressing material through the bottom outlet.

Usually the bottom restriction will be adjusted somewhere within the range of .015 to .030 inch depending upon the characteristics of the material being processed as to proportion of juice to solid constituents, and the character of the solid constituents.

The adjustments provided at the teeth 96 and 97, at the teeth 121 and 123, and the bottom outlet provides a means for regulating the flow of material through the machine and for regulating the percentage of extraction between the two extracting chambers. The teeth 96 and 97 should be adjusted to perform a desirable amount of juice liberation for extraction in the first extracting chamber and to provide a good impelling action on the material.

The teeth 121 and 123 should be adjusted to perform a satisfactory regrind of the material and in addition to provide a mixing up and rearrangement of the material particles to expose fresh surfaces and to facilitate juice liberation. These teeth also must provide a satisfactory downward impelling action to receive the material from the blades 101 and provide a continuous flow to the second extraction chamber.

The bottom outlet at 137 and 139 should be so adjusted as to maintain the comminuted material in the second extracting chamber for a time to insure removal of the desired amount of juice and fine solids. This adjustment must be coordinated with that of the teeth 121 and 123 as well as the teeth 96 and 97 so that a desirable rate of flow is maintained, and a desirable back pressure is provided through the extracting and comminuting zones.

As an example of the different adjustments which are required because of the different characteristics of material being processed, the following adjustments are made: For a material such as apples with a considerable proportion of undesired solid constituents such as core and seeds, the teeth 96 and 97 are spaced .090" apart, teeth 121 and 123 are spaced .033" apart, and the bottom outlet surfaces 137 and 139 are spaced .020" apart. With a leafy material such as cabbage where the proportion of undesired solid constituents is small, the teeth 96 and 97 will be spaced .100" apart, teeth 121 and 123 are spaced .020" apart, and the outlet surfaces 137 and 139 are spaced from .005" to .010" apart.

With certain materials, for example boysenberries, the amount of restriction required at the bottom outlet to obtain a desired back pressure and extraction characteristic is small enough so that the seeds will not pass through without grinding. By providing the separate adjustment at the bottom outlet for this type of material, the teeth 138 and 141 can be spaced to grind the seeds as they pass out with the discharge, while the two sets of comminuting teeth are adjusted to allow passage of the seeds without grinding. In this way, the oil from the seeds is not present in the juice material itself.

It is to be noted that by adjusting the vertical positioning of the rotor, the amount of grind in the second comminuting zone can be adjusted while the machine is running. The amount of adjustment required at the second comminuting zone is sufficiently small with respect to the range of adjustment at the first comminuting zone, so that the desired change in the second comminuting zone will not substantially affect the adjustment at the first comminuting zone. It is to be noted also that the outlet restriction can be controlled while the machine is running by

virtue of the double shaft construction without affecting the other adjustments in the machine.

Referring to the developed view shown in Figure 12, it is to be noted that a spirally arranged path of flow is provided by arrangement of teeth on the rotor. A tooth 96 is disposed immediately adjacent each of the breaker blades to provide a direct path of flow therefrom, and this tooth discharges behind one of the impelling blades 101. A tooth 123 cooperates directly with each of the impelling blades 101 and discharges behind an impelling blade 127. A tooth 141 leads directly from each impelling blade 127. In this way, certain continuous spirally arranged paths of flow are available to control and coordinate the flow of material through the machine. This arrangement also serves to obviate any possible tendency of material to pile up immediately in front of one of the impelling blades.

I claim:

1. In an extractor for juice-bearing materials, said extractor having a stator and a rotor mounted within the stator and defining therewith an annular space providing a path of flow for material, a plurality of annular comminuting zones along said path for liberating juice constituents of the material, each of said zones being defined by cooperating comminuting means on said stator and said rotor, a plurality of juice extracting means along said path, each juice extracting zone following said comminuting zone and comprising annular screening means on said stator and material impelling means on said rotor, said rotor being made up of at least two sections connected for rotation together and for relative axial adjustment.

2. In an extractor for juice-bearing materials, said extractor having a stator and a rotor mounted within the stator and defining therewith an annular space providing a path of flow for material, comminuting means along said path for liberating juice constituents of the material, juice extracting means along said path following said comminuting means, said rotor being made up of at least two sections connected for rotation together and for relative axial adjustment.

3. In an extractor for juice-bearing materials, said extractor having a stator and a rotor mounted within the stator and defining therewith an annular space providing a path of flow for material, a plurality of annular comminuting zones along said path for liberating juice constituents of the material, each of said zones being defined by cooperating comminuting means on said stator and said rotor, a plurality of juice extracting zones along said path, each juice extracting zone following a comminuting zone and comprising annular screening means on said stator and material impelling means on said rotor, said rotor being made up of at least two sections connected for rotation together and for relative axial adjustment, and adjustment means for said sections including at least certain of the supporting bearings for said rotor.

4. In an extractor for juice-bearing materials, said extractor having a stator and a rotor mounted within the stator and defining therewith an annular space providing a path of flow for material, comminuting means along said path for liberating juice constituents of the material, juice extracting means for the resulting comminuted material, said rotor being made up of at least two sections connected for rotation together and for relative axial adjustment, and adjusting

means for said sections including at least certain of the supporting bearings for said rotor.

5. In an extractor for juice-bearing materials, a housing comprising a stator, a rotor disposed within said housing and including shaft sections connected for relative axial adjustment, a supporting bearing for each of said shaft sections, and an adjustable mounting on said housing for each of said bearings to vary the spacing of portions of said rotor from the cooperating portions of said stator.

15 6. In an extractor for juice-bearing materials, a housing comprising a stator, a rotor disposed within said housing and having a part mounted thereon for axial adjustment relative thereto and relative to a cooperating part on said housing, an operating member on said housing, and an adjusting connection from said member to said rotor part to enable adjustment thereof while in rotation.

25 7. In an extractor for juice-bearing materials having a stator and a rotor, cooperating means on said stator and said rotor for comminuting the material, means to provide an outlet for the residual solids after separation of the juice therefrom comprising means fixed to said stator and means cooperating therewith adjustable axially of said rotor and rotatable with said rotor.

30 8. In an extractor for juice-bearing materials having a stator and a rotor, a device for defining an annular passage between said stator and said rotor the axial dimension of which can be selectively adjusted to control the process of juice extraction, said device comprising a first 35 part mounted on said stator, a second part cooperating with said first part to form said passage, means for supporting said second part on said stator adjustable with respect thereto to determine the axial dimension of said passage, and 40 means to rotate said second part from said rotor.

45 9. An extractor for juice-bearing materials having a housing or stator, a rotor disposed coaxially within said stator and spaced therefrom to form a passage for the material, means for 50 separating juice in two stages, means to provide a comminuting zone preceding each of said stages, said zones and stages being arranged along said material passage so that the material first passes through the first comminuting zone, next through the first juice separating stage, then through the second comminuting zone, and finally through the second juice separating stage, means adjustably mounted on said stator to control the passage dimension in the first comminuting zone, means 55 for axially adjusting said rotor to control the passage dimension in the second comminuting zone, and means adjustably mounted on said stator for controlling the dimension of the discharge outlet of said passage.

60 10. An extractor for juice-bearing materials having a housing or stator, a rotor disposed coaxially within said stator and spaced therefrom to form a passage for the material, means for separating juice in two stages, means to provide 65 a comminuting zone preceding each of said stages, said zones and stages being arranged along said material passage so that the material first passes through the first comminuting zone, next through the first juice separating stage, then through the second comminuting zone, and finally through the second juice separating stage, means adjustably mounted on said stator to control the passage dimension in the first comminuting zone, means for axially adjusting said rotor to control 70 the passage dimension in the second comminuting zone.

zone, means adjustably mounted on said stator for controlling the dimension of the discharge outlet of said passage, and means for rotating said last-named means from said rotor.

11. In an extractor for juice-bearing materials, having a stator and a rotor, cooperating means on said stator and said rotor for comminuting the material, means for adjusting the rotor axially to

control the dimension of the passage between said comminuting means, means adjustable relative to said stator to control the discharge outlet for residual solids, said means having a telescopic connection with said rotor whereby vertical movement of said rotor does not affect the adjustment of the discharge outlet.

LEONARD McGIHON.
